HOPPER

John T. Chambers, New Orleans, La., and Werner Lehman, South Milwaukee, Wis.; said Lehman assignor to Bucyrus-Erie Company, South Milwaukee, Wis., a corporation of Delaware

Application January 25, 1935, Serial No. 3,382

8 Claims. (Cl. 214—42)

Our invention relates to new and useful improvements in hoppers, that are more or less continuously loaded, but whose contents are at intervals unloaded into travelling cars.

5 The principal object of our invention is to provide a hopper that is automatically opened to discharge its contents when a car arrives to receive them, and that is automatically closed when the loaded car is removed from beneath the hopper.

10 Another object resides in the provision of a hopper whereby materials of a wet and sticky nature may be received from an excavating machine, accumulated or stored, and discharged into a car more quickly, less expensively, with greater material-clearing facility, requiring less operating power, and in a greatly simplified manner.

15 Another object resides in the provision of a hopper which is peculiarly adapted to conditions existing in the operation of such machines as those shown and described in U. S. Patent No. 1,923,913, issued August 22, 1933, to one of us, namely Chambers.

20 Another object resides in the provision of a tilting hopper whose loads can be discharged more easily, more quickly, less expensively, and with less obstruction to discharging loads.

25 Another object resides in the provision of a hopper of proportionately greater horizontal receiving and discharging sections, in proportion to its weight, and with all sides substantially vertical while discharging its loads.

30 In addition to our principal object, we have worked out a number of novel and useful details, which will be readily evident as the description progresses.

35 Our invention consists in the novel parts, and in the combinations and arrangements thereof, which are defined in the appended claims; and of which one embodiment is exemplified in the accompanying drawings, which are hereinafter particularly described and explained.

40 Throughout the description, the same reference number is applied to the same member or to similar members.

45 Referring to the accompanying drawings, it will be seen that:

Figure 1 is a side view, partly in elevation and partly in section, of our hopper and associated mechanism, in extreme dumping position, with

part of the receiving car shown in section below it.

Figures 2 to 5 show the material parts of the structure of Figure 1, but in successive stages of closing, as will be more particularly explained as 5 the description progresses.

Referring more particularly to Figure 1, the parts will now be described as follows. It is to be understood that many of the elements occur in pairs, of each of which pair for simplicity only 10 one element is herein shown.

11 is a part of the main frame of the general assembly of which our hopper forms a part. Carried thereby are brackets 12, of which one is shown, to journal support trunnions 13, of 15 which one is shown, for the rotation of the hopper-bottom 14.

Integral with this bottom are sides 15 and beams 16, of each of which but one is shown. The beams, of which there may be four or five, 20 serve the dual purpose of stiffening the bottom and of contacting the roller or rollers herein-after described. These beams are of I-construction, the bottom flange thereof being curved at one end as shown, so as to perform the function 25 hereinafter defined.

The door 17 of the hopper does not move with the hopper, but is carried rigidly by the main frame 11, by means of brackets 18, of which one is shown, so that we have the situation of the 30 door remaining fixed and the hopper opening, instead of vice versa as is usual.

These brackets 18 also carry latches 19, actuating springs 20 therefor, and bell-crank 21. Latch-operating lever 22 is pivoted on the main 35 frame 11, and is connected with bell-crank 21 by means of rod 23. The exact arrangement of all this chain of control is quite immaterial, provided that the items thereof are so positioned and proportioned as to function as hereinafter 40 described.

On rails 24, of which one is shown, runs a car 25, the details of which are immaterial to the present invention. This car is pulled in one direction by ropes 26, of which one is shown; and 45 in the other direction by ropes 27, of which one is shown.

The car carries a roller or rollers 28, to engage the beams 16; and a shoe 29, to engage the lever 22. It is to be understood that these rollers 28 50

and this shoe 29 can be combined into two means or a single means performing the functions of both the shoe and the rollers. Accordingly when we recite two "means moving with the car", this 5 will be satisfied by but a single means, performing the functions of both.

There may be a bumper 30, to limit the travel of the car to the left.

On each side 15 of the hopper, there is a 10 notched plate 31, carrying a somewhat thickened catch 32 for the latch 19.

Commencing with Figure 5, we shall now describe the opening of the hopper. This figure shows the hopper closed, and the car 25 approaching from the right.

In Figure 4, the car has progressed a little further to the left, so that the rollers 28 have engaged the beams 16, lifting the hopper slightly, and thus freeing the catches 32 from the latches 20 19.

Further movement to the left, as shown in Figure 3, results in the shoe 29 engaging the latch-operating lever 22, whereby through the resulting motion of rod 23 and bell-crank 21, the latches 25 19 are retracted. Thereupon the roller 28, engaging the beams 16, gently lowers the hopper past the latch-engaging position, while the latches 19 are still held retracted.

In Figure 2, the hopper is lowered still further; and, as there is no need to hold the latch retracted, it is released.

In Figure 1, the hopper has reached its extreme open position, for dumping into the car 25.

Please note that, throughout the opening of 35 the hopper, it is gradually eased open, by virtue of the continuing contact between the beams 16 on the door, and the rollers 28 on the car.

After the car is filled by the discharge of the hopper into it, the car is pulled to the right again 40 by ropes 27. The hopper and associated parts occupy successively the positions shown in Figures 1 to 5. The rollers 28, by bearing against the beams 16, gradually close the door. As the catch 32 approaches the latch 19, the shoe 29 45 engages the lever 22, which acting through rod 23 and bell-crank 21, retracts the latch 19 as shown in Figure 3.

The action of the rollers 28 on the beams 16, continues to raise the catch 32 to above the latching position, whereupon the shoe 29 clears the lever 22, letting the latch 19 slide into latching position, under the influence of the spring 20, all of which is as shown in Figure 4.

Then the rollers 28 gradually clear the beams 55 16, thus gently lowering the catch 32 onto the latch 19, as shown in Figure 5.

The car then continues on its journey to the right, to the place where its contents are to be dumped. The mechanism necessary to empty 60 the car, being no part of this invention, is not shown.

Having now described and illustrated one form 65 of our invention, we wish it to be understood that our invention is not to be limited to the specific form or arrangement of parts hereinbefore described, except in so far as such limitations are specified in the appended claims.

We claim:

1. In combination: a fixed hopper-door; a 70 tiltable normally substantially horizontal hopper, biased to open under the influence of gravity; a latch to hold the hopper closed against this bias; a latch-operating member, operatively connected to the latch; a hopper-operating member, oper-

atively connected to the hopper; a car, slideable horizontally to and from a load-receiving position beneath the hopper; means, moving with the car, to engage the latch-operating member, to unlatch the latch; and means, moving with the car, to engage the hopper-operating member, to lift the hopper off the latch and then ease it open, when moving in one direction, and to close the hopper to above the latching position and then lower it onto the latch when moving in the 10 other direction.

2. In combination: a hopper-door; a tiltable normally substantially horizontal hopper, biased to open; a latch to hold the hopper closed against this bias; a latch-operating member, operatively connected to the latch; a hopper-operating member, operatively connected to the hopper; a car, slideable horizontally to and from a load-receiving position beneath the hopper; means, moving with the car, to engage the latch-operating member, to unlatch the latch; and means, moving with the car, to engage the hopper-operating member, to ease the hopper open, when moving in one direction, and to close and latch the hopper, when moving in the other direction. 20

3. In combination: a fixed hopper-door; a tilt-able hopper, biased to open under the influence of gravity; a latch to hold the hopper closed against this bias; a latch-operating member, operatively connected to the latch; a hopper-operating member, operatively connected to the hopper; a car, slideable to and from a load-receiving position beneath the hopper; means, moving with the car, to engage the latch-operating member, to unlatch the latch; and means, moving with the car, to engage the hopper-operating member, to lift the hopper off the latch and then ease it open, when moving in one direction, and to close the hopper to above the latching position and then lower it onto the latch when moving in the other 40 direction.

4. In combination: a hopper-door; a tiltable hopper, biased to open; a latch to hold the hopper closed against this bias; a latch-operating member, operatively connected to the latch; a hopper-operating member, operatively connected to the hopper; a car, slideable to and from a load-receiving position beneath the hopper; means, moving with the car, to engage the latch-operating member, to unlatch the latch; and means, moving with the car, to engage the hopper-operating member, to ease the hopper open, when moving in one direction, and to close and latch the hopper, when moving in the other direction. 50

5. A hopper, comprising: a hopper bottom; support means appropriately adapted to the tilting of the hopper in a vertical plane; hopper sides, integral with the bottom, and higher toward the discharge end of the bottom; beams, serving both to stiffen the bottom, and as runners, to ease the 60 bottom open and to close it; and a latch element on the hopper at a substantial radial distance from the axis of tipping, serving to hold the hopper closed.

6. A hopper, comprising: a hopper bottom; support means appropriately adapted to the tilting of the hopper in a vertical plane; hopper sides, integral with the bottom, and higher toward the discharge end of the bottom; beams, serving both to stiffen the bottom, and as runners, to ease the 70 bottom open and to close it; a latch element on the hopper at a substantial radial distance from the axis of tipping, serving to hold the hopper closed and a stationary hopper-door.

7. A hopper, comprising: a hopper bottom; 75

support means appropriately adapted to the tipping of the hopper in a vertical plane; hopper sides, higher toward the discharge end of the bottom; beams, serving both to stiffen the bottom, and as 5 runners, to ease the bottom open and to close it; and a latch element on the hopper at a substantial radial distance from the axis of tipping, serving to hold the hopper closed.

8. In combination: a fixed substantially vertical 10 hopper-door; a hopper, comprising a bottom

downwardly inclined toward the bottom of the fixed door, and two substantially vertical sides higher toward the discharge end of the bottom; a pivot for the hopper, so positioned that the hopper when loaded will be biased by gravity to tilt 5 open; and releasable means for holding the hopper closed against such bias.

JOHN T. CHAMBERS.

WERNER LEHMAN.
